UNITED STATES PATENT OFFICE.

JOHN T. WELLS, OF SCOTTSVILLE, NEW YORK.

SILO.

1,236,516.

Specification of Letters Patent. Patented Aug. 14, 1917.

Application filed April 14, 1915. Serial No. 21,382.

To all whom it may concern:

Be it known that I, JOHN TALCOTT WELLS, a citizen of the United States, residing at Scottsville, in the county of Monroe and State of New York, have invented certain new and useful Improvements in Silos, of which the following is a specification.

My invention is designed as an improved storing structure and relates particularly to silos of that type comprising a plurality of complementary or interlocking silo sections.

The invention consists in the novel construction, combination and arrangement of parts to be hereinafter described and particularly pointed out in the claims.

In the drawings:

Figure 1 is a front elevation of the silo; Fig. 2 is an enlarged section on the line 2—2 of Fig. 1;

Fig. 3 is a fragmentary vertical sectional view partly in section;

Fig. 4 is a perspective view partly in section, illustrating the arrangement of the silo sections;

Fig. 5 is a detail perspective view of one of the spacing hoops;

Fig. 6 is a fragmentary cross sectional view; and

Fig. 7 is a detail perspective view of one of the interlocking metallic sections.

Like numerals of reference designate like or corresponding parts throughout the several views.

Proceeding now with a description, 1 designates as an entirety the outer silo shell or wall and 2 as an entirety a similarly constructed inner silo shell or wall. Each wall is made or built up of a plurality of interlocking complementary vertically disposed 40 boards or strips designated 3, the same, when assembled, forming a structure comprising, as suggested, an inner and outer wall, circular in cross section. The silo roof, designated 4, may be of any suitable or accepted design.

In its preferred embodiment, the interior structure, or the structure intermediate the mentioned walls, may be said to consist of a plurality of hoops or bands, preferably 50 sectional, the several bands, by reason of the arrangement noted, bracing the silo at intervals throughout.

The silo here shown is mounted or built

upon a plastic bed or foundation 4', one of the interior hoops or bands, designated 5, 55 being flanged as indicated at 6 to fit a circular groove therefor 7 formed in the mentioned bed. The hoop or band 5 consists of a plurality of segment sections (preferably three) arranged end to end and fastened in the manner shown to advantage in Fig. 6. Said hoop or band is provided with a circular flange 8 which, with a like flange 9 formed upon a second hoop or band 10 is adapted to form a circular groove within 65 which the lower marginal edge of a dividing plate 11 is fitted. Band 10, like the band 5, is adapted to rest upon the concrete bed or foundation and comprises, like the said band 5, a plurality of segment sections 70 arranged end to end. While no flange similar to that designated at 6 is shown forming a part of the band 10, it is to be understood that such may be provided, if desired. Hoops 5 and 10 abut throughout their entire circumference, hoop 10 being the smaller and therefore positioned innermost.

Between the inner wall 2 of the silo and the hoop 10 is arranged a thin water proof substance such as waterproofed paper, said 80 substance being designated 12 and of such size as to extend vertically throughout the length of the silo. That the substance 12 may be spaced from the inner wall 2 I interpose between said inner wall and the mentioned substance a spacing strip or band 13, said band like the mentioned bands 5 and 10 resting upon the foundation 4'. Water proof material 14 preferably lines the outer surface of the inner wall structure 2, said 90 lining being interposed between the band 13 and the said inner wall.

Water proof material 15 is interposed between the band or hoop 5 and a circumferentially divided hoop or band 16, the latter 95 embracing the mentioned band 5, the division, as pointed out, affording a space 17 for a plurality of reinforcing cables 18 which are adapted to encircle the hoops or bands 5 and 10 to preclude relative displacement of the bands. The outer silo wall structure 1 is lined with waterproof material as indicated at 19, said material being interposed between the dividing strips 16 and the said outer wall. The several 105 strips 12, 14, 15 and 19 extend vertically

throughout the length of the silo and, with the dividing and supporting plate 11, form a plurality of spaces or chambers 20, said chambers, as will hereinafter appear, affording a means whereby heat and cold are excluded from the interior of the silo. The several lining strips will preclude leakage of the silo contents.

The arrangement of hoops and bands described as engaging the bed or foundation 4' has been duplicated at intervals throughout the height of the silo, the plate 11 supporting the hoops and bands other than the lowermost. All of the hoops and bands constituting a single series are laterally alined and joined together, attaching plates 21 being provided for that particular purpose. The plates 21 overlap the segments constituting the bands 5 and 10, the said plates being affixed (by any suitable means) to said abutting segments to thereby preclude displacement of the segments and maintain the hoops and bands constituting the several series at all times laterally alined.

Upon reference to Fig. 3 it will be noted that the plate 13 is mounted to engage between flanges formed upon the bottom edges of the hoops 5 and 10 constituting the series next above the series illustrated at the bottom of said Fig. 3.

Openings 22 may be formed in the silo, one above the other, each opening being normally closed by a hinged silo door 25, suitable fastening means such as is indicated at 24 maintaining the several doors normally in a closed position.

From the foregoing, taken in connection with the accompanying drawings it will be noted that displacement of the silo body is prevented by the fitting engagement of the flange 6 within the groove therefor; that the chambers formed interiorly of the silo wall will preclude passage of heat and cold therethrough; and that by extending the cables 18 circumferentially of each series of hoops, the several hoops are firmly fastened one to the other and in lateral alinement thereby bracing and holding the boards constituting the inner silo wall against separation after continued use.

The outer silo wall 1 may be nailed or otherwise fastened in place and against movement with respect to the inner silo wall.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrific-

ing any of the advantages of my invention, 65 as defined in the appended claims.

Having thus fully described my invention, what I claim as new and desire to secure by Letters Patent, is:—

1. In a silo, an inner structure, an outer structure, superimposed hoops interposed between the mentioned structures, each hoop comprising a plurality of segment sections, dividing plates positioned to extend vertically between the mentioned structures, the 75 dividing plates forming interior chambers, and means on the hoops to support the plates against lateral displacement, the plates affording a support for the several superimposed hoops.

2. In a silo, an inner structure, an outer structure, a plurality of series of hoops arranged to embrace the inner structure and to space the outer structure therefrom, the several series being arranged in superimposed relation, the hoops constituting the several series comprising a plurality of segment sections, flanges formed upon two of the hoops included in said series, a dividing plate engaging the flanges of adjacent series, the flanges precluding lateral displacement of the mentioned plate, said plate affording a support for the mentioned series, and means embracing the outermost hoops of each series to preclude displacement of 95 the several hoops constituting said series.

3. In a silo, an inner structure comprising a plurality of interlocking strips, an outer structure comprising a plurality of interlocking strips, a plurality of series of hoops arranged to embrace the inner structure and to engage the outer structure, the hoops maintaining the outer structure spaced from the inner structure, a vertical dividing plate arranged between the mentioned structures to form chambers in the wall of the silo, means to lock said plate against displacement, the plate in turn affording a support for the series of hoops positioned one above the other, and means embracing each 110 series of hoops to lock the hoops constituting said series against displacement.

4. In a silo, an inner structure, an outer structure, a plurality of series of hoops arranged to embrace the inner structure at 115 spaced intervals throughout its height, each series of hoops comprising a plurality of segment sections, means to fasten the abutting terminals of the several sections, means embracing each series of hoops to preclude 120 displacement, and dividing plates engaging the hoops and with the hoops dividing the silo wall into a plurality of chambers.

5. In a silo, an inner structure, an outer structure, a plurality of series of hoops arranged to embrace the inner structure at intervals throughout its height to maintain the outer structure uniformly spaced therefrom,

each hoop included in each series comprising a plurality of segment sections, means to fasten the abutting terminals of the several sections, means embracing the hoops to pre-
clude displacement, flanges formed at the top and base of each series of hoops, a di-
viding and supporting plate engaging the flanges of each series to form in the silo wall a plurality of chambers, and a bed support
10 for the silo provided with a groove within

which the lowermost flange of the lowermost series is fitted, the last mentioned en-
gagement precluding lateral displacement of the silo.

In testimony whereof I affix my signa- 15
ture in presence of two witnesses.

JOHN T. WELLS.
